U. S. OIL AND SERVICE CORPORATION, OF NEW YORK, N. Y., A CORPORATION OF NEW
YORK

PULVERIZED FUEL SUPPLYING MEANS FOR INTERNAL COMBUSTION ENGINES

Application filed October 21, 1929. Serial No. 401,330.

This invention relates to pulverized fuel supplying means for internal combustion engines. One object of the invention is to supply pulverized fuel to internal combustion engines by means of an air stream in which the fuel is suspended and from which stream the various cylinders of the engine can be supplied with the proper admixture of fuel and air.

10 Another object of the invention relates to the provision of means for preventing the accumulation of fuel around the fuel intake valves of the engine, or other valves, and to return any such deposited fuel ultimately to the fuel stream.

Other objects relate to various features of construction and arrangement of parts which will be apparent from a consideration of the following specification and accompanying 20 drawings, wherein:

Fig. 1 is a vertical partial sectional view of an internal combustion engine illustrating an embodiment of the invention;

Fig. 2 is a horizontal sectional view taken 25 on line 2—2 of Fig. 1;

Fig. 3 is a transverse vertical section taken on line 3—3 of Fig. 1; and

Fig. 4 is a sectional view taken on line 4—4 of Fig. 3.

30 In the drawings, 10 indicates cylinders of an internal combustion engine each having a piston 11 therein. The present improvements are directed merely to the supplying of an explosive mixture of pulverized fuel and air 35 to the cylinders and is not concerned with matters of lubrication or ignition, any suitable means being provided to perform these necessary functions.

40 In carrying out the present improvements a supply of pulverized fuel, which may be pulverized coal, will be maintained in a suitable receptacle 12 from which the fuel is conveyed through pipe 13 to a chamber 14. A blower 15 is arranged to force a draft of air 45 through the chamber 14 and into and through the pipe 15^a, which air will pick up the fuel in the chamber 14 and carry it along in a suspended state, and any unused fuel not abstracted from the pipe or manifold 15 will 50 be carried by the stream back through the

connecting pipe 16 into an air extractor 17 of any suitable construction. The reclaimed fuel from the extractor 17 will be returned to the fuel reservoir or supplying means by means of the conduit 18.

55 The pipe 15^a communicates with the various cylinders 10, through intake conduits 19, in which are positioned valve stems 20 and 21 each of which has a valve closing member at each end. The stem 20 has a valve 22 at its 60 lower end which closes the intake port 23 of the cylinder and a second valve 24 which regulates the passage of the fuel from the pipe 15 into the conduit 19. The valve stem 20 is arranged to reciprocate vertically for 65 effecting the opening and closing of the fuel ports. As shown in Fig. 3, this movement of the valve stem 20 may be effected by means of a rocker arm 25 which is operated by a push rod 26, the lower end of which contacts with a cam 27 of the cam shaft 28 which is operated by any suitable means by the engine.

The valve stem 21 for each cylinder is reciprocated horizontally, which movement may be effected by means of a rocker arm 29 having a roller 30 which bears against a push rod 31 having a cam surface 32 thereon. Push rod 31 may be operated in properly timed relation by the cam 33 of the second cam shaft 34, although if desired the rocker arms 25 and 29 can be arranged on the same 70 side of the engine and operated from suitable cams provided on a single cam shaft.

75 While the blower 15 is operating and a supply of pulverized fuel is being delivered to the chamber 14, a stream of mixed air and fuel will be forced through the pipe 15^a and upon the suction stroke of any piston, the valves 22 and 24 will be in open position whereby a charge of explosive mixture will 80 be drawn into the respective cylinder 10. Upon the compression stroke of the piston the valves 22 and 24 will be closed. The closing of the valve 24 will entrap a certain amount of the mixture within the respective 85 conduit 19 which might cause a fouling of the valve 22 or an accumulation of fuel which would from time to time be drawn into the cylinder and provide an improperly proportioned mixture of fuel and air. To remove 90

the entrapped fuel from the conduits 19, I provide a second blower 35 which directs a blast of air through pipe 36 and into the left hand conduit 19. If the valves 21' carried by the valve stem 21 are in open position, the air will pass through the pipe 19 horizontally and remove the entrapped fuel and will pass into pipe section 37 and through port 38 into the branch pipe 39 and pipe 40 into the air extractor 17. When any of the valves 21' are closed, the stream of air entering the left hand end of the respective conduits 19 will pass through its port 41 through the by-paths 42 and into pipe section 37 through port 43 and thence thru the second conduit 19 if the valves 21' are open. If they are not open, the air will pass through the by-paths 43 to the next intermediate pipe section 37 and so on, the air stream dividing as it moves to the left and portions thereof passing through the pipes 39 to pipe 40 and thence to the air extractor 17.

The cams that operate the respective valve stems 21 are arranged to move the valves 21' to closing position to shut off the air current from the blower 35 while the valves 24 are in open position admitting fuel into the cylinder upon its intake stroke.

By the arrangement shown, a constantly circulating stream of explosive fuel is available for each cylinder, which constant movement of the stream prevents the settling out of the finely pulverized fuel. To guard against improper proportions of fuel and air in the conduit 15, means are provided for removing surplus fuel which may be fed through pipe 13. As shown in Fig. 1, the chamber 14 is somewhat larger in cross-section than the conduits communicating therewith. This enlarged chamber 14 thus causes a local decrease in the air velocity from the blower 15 which permits excess fuel to settle out of the air stream into the collecting chamber 46 in which is positioned a valve stem 47 having upper valve 48 and lower valve 49, the former controlling communication between chambers 14 and 46 while valve 49 controls communication between chamber 46 and the pipe 36. Any suitable means may be provided for operating the valves 48 and 49 periodically whereby when valve 48 is open, valve 49 is closed to permit excess fuel to collect in chamber 46. When the relation of the valves is reversed, the accumulated fuel will be drawn from the chamber 46 by the air stream in pipe 36 and be carried to the extractor 17. In Fig. 1 the illustrative means shown for operating the valves 48 and 49 comprise a lever 50 operatively connected to the stem 47 and extending through the wall of the chamber 47, the lever being pivoted in the wall aperture at 51. The outer end of the lever 50 may have an anti-friction roller 52 which is operated on by a cam 53 for periodically shifting the valves 48, 49. The

cam may be mounted on a rotary shaft 54 having a worm gear 55 in engagement with a worm 56 mounted on the shaft of the blower 15. A spring 57 shifts the lever 50 to return the valves 48 and 49 to closed and open positions respectively, after the cam 53 moves out of contact with the roller 52.

In Fig. 1 the cylinders are shown provided with outlet valves 55 which may be of conventional construction, or any other arrangement may be used as the construction of the cylinder per se, the exhausting of the product of combustion, the means for fixing the charge within the cylinder, and problems of lubrication are per se no features of the present improvements, although as to firing, spark plugs may be used or the charge may be ignited by heat of compression as in engines of the Diesel type.

Although I have shown and described an embodiment of my improvements for the purpose of illustration, I do not wish to be restricted specifically thereto except as so limited by the appended claims.

What I claim is:

1. The combination with an internal combustion engine having one or more cylinders, of means for supplying pulverized fuel thereto comprising a header, means for forcing air therethrough, means for feeding pulverized fuel to the air stream to be carried in suspension therein, valved conduits establishing communication between said cylinders and said header when said valves are open whereby charges of fuel are abstracted from said header upon the suction strokes of said engine, means for opening and closing the respective valves in timed relation with reference to the piston strokes, and means for removing entrapped fuel from each of said conduits while said valves are closed.

2. The combination with an internal combustion engine having one or more cylinders, of means for supplying pulverized fuel thereto comprising a header, means for forcing air therethrough, means for feeding pulverized fuel to the air stream to be carried in suspension therein, valved conduits establishing communication between said cylinders and said header when said valves are open whereby charges of fuel are abstracted from said header upon the suction strokes of said engine, means for opening and closing the respective valves in timed relation with reference to the piston strokes, and means for removing entrapped fuel from each of said conduits while said valves are closed, said last named means comprising air blasting mechanism having passages communicating with each of said conduits.

3. The combination with an internal combustion engine of means for supplying pulverized fuel thereto comprising a header, means for forcing air therethrough continuously during the operation of the engine,

- means for supplying pulverized fuel to the air stream whereby the fuel is carried in suspension thereby, branches from said header affording communication between said header and engine cylinders whereby charges of fuel are drawn from said header upon the suction strokes of said engine, a pair of valves in each of said conduits for closing the fuel inlet and outlet ports thereof simultaneously, 5 such fuel from said chamber and conveying it to said supply member, and means for closing communication between said settling chamber and collecting chamber during the removal of fuel from the latter. 70
- 10 means for opening said valves upon the suction stroke of the respective engine pistons and closing said valves during the remainder of the operating cycle, said conduits having air inlet and outlet ports in its side walls, 75
- 15 a second pair of valves in each conduit for simultaneously opening or closing said last named ports, means for actuating each of said second pairs of valves to open position when the respective first valves are closed 80
- 20 and vice versa, and air blasting means adapted to force air through said second ports when the valves thereof are open for removing fuel entrapped in the conduits upon the closing of the respective first mentioned 85
- 25 valves. 90
4. The combination with an internal combustion engine of a pulverized fuel supply member, a delivery conduit communicating therewith, means associated with said conduit 95
- 30 for maintaining in the latter a stream of air carrying pulverized fuel in suspension from which stream explosive charges are abstracted by the engine upon the suction strokes thereof, and means for removing excess fuel 100
- 35 from the air stream to provide a proper admixture of air and fuel, said last named means comprising a settling chamber. 105
5. The combination with an internal combustion engine of a pulverized fuel supply member, a delivery conduit communicating therewith, means associated with said conduit for maintaining in the latter a stream of air carrying pulverized fuel in suspension from which stream explosive charges are abstracted by the engine upon the suction strokes thereof, means for removing excess fuel from the air stream to provide a proper admixture of air and fuel, said last named means comprising a settling chamber, a collecting chamber into which the excess fuel is discharged, and means for returning said fuel from said collecting chamber to the fuel supply means. 110
- 45 50 55 60 65 70 75 80 85 90 95 100 105 110 115 120 125 130
6. The combination with an internal combustion engine, of a pulverized fuel supply member, an air conduit into which fuel is discharged from said member, means for forcing air through said conduit for carrying the fuel in suspension therein, means for admitting charges of said fuel and air into said engine on the suction strokes thereof, a velocity reduction chamber in said conduit to permit excess fuel to settle out of the air stream, a collecting chamber into which such surplus fuel is discharged from said settling chamber, means for intermittently removing 130

In testimony whereof, I have subscribed my name.

LAURENCE C. BOWES.
